UNITED STATES PATENT OFFICE.

GIUSEPPE VITULLI MONTARULI, OF ROME, ITALY.

CONSTRUCTION OF SHIPS.

1,345,213.

Specification of Letters Patent. Patented June 29, 1920.

Application filed June 4, 1919. Serial No. 301,619.

To all whom it may concern:

Be it known that I, GIUSEPPE VITULLI MONTARULI, a subject of the King of Italy, and residing at 9 Piazzale Flaminia, Rome, 5 Italy, have invented certain new and useful Improvements in the Construction of Ships, of which the following is a specification.

My invention relates to the construction 10 of surface-going ships and consists of an improved form of hull of the type described in my previous Patent Number 1,295,786, granted Feb. 25, 1919, in which the waist of the ship has curved transverse frames 15 throughout and the end portions have frames whose cross-section is formed of circular segments above and below and straight lines of gradually increasing length laterally.

According to the present invention the 20 transverse frames of the central portion of the hull are not in the shape of a continuous curve of, for example, circular, elliptical or oval cross section, but the curve is interrupted at points by straight lines connecting with the curved parts.

The invention is illustrated by way of example in the accompanying drawing, in which—

Figure 1 shows on the left-hand side the 30 midship section of the hull and on the right-hand side the curvature of this section,

Fig. 2 shows the hull divided into three parts of different geometrical shape,

Fig. 3 shows in plan and Figs. 4 and 5 35 in projections of vertical sections, the shape of the hull forward and aft.

In Fig. 1, the curved portion A, B, C is a semi-circle which has its center at D and 40 connects at its ends A and C with rectilinear parts A E and C F so as to make up a frame which consists of a circular part A, B, C and of rectilinear parts E A and C F above and below to form half a section of 45 the central part 3 in Fig. 2 of the hull.

The forward end 4 (Fig. 2) is built up from section 6 of midship section onward with the aid of sections 7, 8, 9, 10 and 11 which consist of circular arcs connected by 50 straight lines above and below and of gradually increasing lines at the sides, until they reach the forward end 12 with an entirely rectilinear vertical section.

The sections of the after end 5 (Fig. 2) 55 are similar to those of the forward end and

they extend onward from the last section 13 of midship section so as to reach gradually along sections 14, 15, 16, 17 and 18 the rectilinear vertical stern section 19, the only difference between the forward and after 60 end portions being that the latter is tapered below so as to leave there a free space for the working of the screws.

The shape of the hull built up in the 65 above described manner allows of its main parts being constructed with interchangeable elements of constant curvature, whereby a standardization of the construction is attained for building ships in series.

As regards the central portion of the 70 ship, this construction is shown in cross section at 1 on the left and diagrammatically at 2 on the right hand side of Fig. 1. In this central part the section of the hull consists substantially of a frame 20 75 which may have the section of any ordinary bar used in shipbuilding, and of layers of plates to form the outer plating 21.

A double bottom 22 may have any desired 80 shape, and 23 is a hatchway and 24 a section of the deck in communication with the hatchways.

It is to be understood that the rectilinear interruption or interruptions of the curve which forms the cross section of the waist, 85 may be provided at any desired or appropriate point or points, for example, above and below, as described, or laterally, and so on.

What I claim is:

1. A ship having a plurality of transverse frames, the frames throughout the waist of the ship being in the shape of a plane curve interrupted at points by straight lines, and the end portions having 95 similar frames with straight lines at the sides of gradually increasing length.

2. A ship having a plurality of transverse frames, the frames throughout the waist of the ship being in the shape of a curve interrupted at points by straight lines and the end portions having cross sections formed of similar curved sections having vertical straight portions of gradually increasing length toward the ends.

3. A ship having a plurality of transverse frames, the frames throughout the waist of the ship being in the shape of a curve interrupted at points by straight lines and the end portions have cross sections 110

90

105

formed of curved segments with straight lines above and below and straight lines of gradually increasing length at the sides, the frames of the after end being shaped so as 5 to provide for the said end being tapered below.

In testimony whereof I have signed my

name, in the presence of two subscribing witnesses, at Rome this 3rd day of May, 1919.

GIUSEPPE VITULLI MONTARULI.

Witnesses:

**LUIGI EMILIOASI,
FORTUNI BOSALLO.**
